UNITED STATES PATENT OFFICE

136,976

DESIGN FOR A BABY'S NURSING BOTTLE OR SIMILAR ARTICLE

Alvin H. Ostrin, Charleston, W. Va.

Application October 29, 1943, Serial No. 111,530

Term of patent 14 years

To all whom it may concern:

Be it known that I, Alvin H. Ostrin, a citizen of the United States, residing at Charleston, in the county of Kanawha and State of West Virginia, have invented a new, original, and ornamental Design for a Baby's Nursing Bottle or Similar Article, of which the following is a specification, reference being had to the accompanying drawing, forming a part thereof.

Figure 1 is a side elevational view of a baby's nursing bottle or similar article showing my new design; and

I claim:

The ornamental design for a baby's nursing bottle or similar article, as shown.

ALVIN H. OSTRIN.
